Primary Examiner—Cathron C. Brooks*(74) Attorney, Agent, or Firm*—Woodard, Emhardt,
Naughton, Moriarty & McNett(57) **CLAIM**

The ornamental design for a divot tool display box, as shown and described.

DESCRIPTION

FIG. 1 is a top perspective view of my new design for a divot tool display box.

FIG. 2 is a front elevational view of my new design.

FIG. 3 is a right side-elevational view of my new design, the left side-elevational view being a mirror image.

FIG. 4 is a top plan view of my new design.

FIG. 5 is a bottom plan view of my new design; and,
FIG. 6 is a rear elevational view of my new first embodiment design.

The broken lines shown are for illustrative purposes only and form no part of the claimed design.
